ATTORNEY

UNITED STATES PATENT OFFICE

92,852

DESIGN FOR A FOUNTAIN PEN AND PENCIL CLIP

Clinton E. Marshall, New York, N. Y.

Application March 15, 1934, Serial No. 51,055

Term of patent 7 years

To all whom it may concern:

Be it known that I, CLINTON E. MARSHALL, a citizen of the United States, and residing at New York, in the county of New York and State of New York, have invented a new, original, and ornamental Design for a Fountain Pen and Pencil Clip, of which the following is a specification, reference being had to the accompanying drawing, forming part thereof.

Fig. 1 is a face view of a fountain pen and pencil clip, showing my new design; and,

Fig. 2 is a side edge view thereof.

I claim:—

The ornamental design for a fountain pen and pencil clip as shown.

CLINTON E. MARSHALL.
